UNITED STATES PATENT OFFICE.

ALFRED HARRIS, OF KNOXVILLE, TENNESSEE.

DESIGN FOR A BUTTON OR BADGE.

SPECIFICATION forming part of Design No. 24,868, dated November 12, 1895.

Application filed May 22, 1895. Serial No. 550,272. Term of patent 3½ years.

To all whom it may concern:

Be it known that I, ALFRED HARRIS, a citizen of the United States, residing at Knoxville, in the county of Knox and State of Tennessee, have invented and produced a new and original Design for Society and Campaign Buttons or Badges, of which the following is a specification, reference being had to the accompanying drawings, showing a part hereof.

In the drawings, Figure 1 represents a plan of a badge embodying my design. Fig. 2 is a sectional perspective view of the same.

My design consists, essentially, of a disk, the front face or surface of which has two plain circular fields thereon contrasting in color, one field being comparatively very large and the other quite small, the smaller field being clearly defined by a boundary-line from the larger field or face of the disk and contained within a quadrant thereof and having its boundary-line at one point coincident with or cut into the boundary-line of the larger field or margin of the disk. The face of the larger field is marked with the figure "16," while the smaller field is marked with the figure "1."

The disk is provided on its rear face with a projection or stud.

Referring to the drawings, A represents the disk, the greater portion of which presents a plain circular field of a suitable color, as white, containing within its boundaries a small circular field B of a different color, as yellow, so as to present the desired contrast in colors, the smaller field being contained within a quadrant of the larger field and having its boundary-line clearly defined and coincident with or cut into the boundary-line or margin of the larger field or disk at its circumference.

C denotes the stud or projection on the back of the disk.

Having thus described my invention, what I claim, and desire to secure by Letters Patent of the United States, is—

The design for a badge substantially as herein shown and described.

ALFRED HARRIS.
